UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL-PATTERN.

Specification forming part of Design No. 6,841, dated September 2, 1873; application filed August 9, 1873.
[Term of Patent 3½ years.]

F.

To all whom it may concern:

Be it known that I, FREDERICK WINK, of the city and county of Philadelphia, State of Pennsylvania, have invented a Design for Shawl-Pattern, of which the following is a specification:

The main feature of my design is the stripe A, one half of which is shown by the figure in the accompanying drawing, the remainder being merely a repetition of that which appears. The stripe is composed of a series of minor parallel stripes, bars, or ribs of different shades or colors arranged in groups, and some being

strongly contrasted, and others blended or shaded into each other, as shown.

Irrespective of the colors employed, I claim—

The design for a shawl-pattern, as represented in and by the accompanying drawing.

In testimony whereof I have signed my name to this specification in the presence of two subscribing witnesses.

FRED. WINK.
